US0D1023183S

(12) **United States Design Patent** (10) Patent No.: **US D1,023,183 S**
(45) Date of Patent: ** Apr. 16, 2024

(54) **SPORT DUMBBELL**

(71) Applicant: **Caifeng Zhang**, Shuixi Town (CN)

(72) Inventor: **Mengdi Zhang**, Cangzhou (CN)

(73) Assignee: **Caifeng Zhang**, Ninghua (CN)

(**) Term: **15 Years**

(21) Appl. No.: **29/856,855**

(22) Filed: **Oct. 18, 2022**

(51) LOC (14) Cl. **21-02**

(52) U.S. Cl.

USPC **D21/682**

(58) **Field of Classification Search**

(57) **CLAIM**

The ornamental design for a sport dumbbell, as shown and described.

DESCRIPTION

FIG. 1 is a top perspective view of a sport dumbbell, showing my new design;

FIG. 2 is a bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.
